ISAAC DE KAISER AND ALONZO B. BARRETT, OF WILKINSBURG, PENNSYLVANIA.

GOLF-BALL TEE.

1,176,039.

Specification of Letters Patent. Patented Mar. 21, 1916.

Application filed August 26, 1914. Serial No. 858,620.

To all whom it may concern:

Be it known that we, ISAAC DE KAISER and ALONZO B. BARRETT, citizens of the United States, and residents of Wilkinsburg, in the county of Allegheny and State of Pennsylvania, have invented a new and useful Improvement in Golf-Ball Tees, of which the following is a specification.

Our invention relates to tees for golf balls, and it has for its object to provide a tee that is not only convenient, economical and clean to use, but that is also soluble so that, even if it is broken or lost, it will not litter up the golf course because, being soluble, it will dissolve and disappear when it rains, or from the effects of dew.

Our invention is illustrated in the accompanying drawing, the two figures of which represent two different modified forms of the tee.

The tee of Figure 1 is in the form of a shell 1 having a substantially hemispherical end that is preferably apertured at 2 to provide a seat for a golf ball 3. This shell or tee is composed of gelatin, or some other material that will readily dissolve in the rain or dew, but that, when in a dry condition, is of sufficient hardness and rigidity to retain its shape. The tee of Fig. 2 is also composed of a soluble material, but is in the form of a truncated conical shell having a recess or seat in its smaller end adapted to receive the golf ball. This form lends itself to more ready packing of the tees, because they may be nested and thus a large number of them may be caused to occupy but a small amount of space. The tee of Fig. 1 may also be modified slightly in form to lend itself to close nesting and compact assembling of a quantity of the tees.

We are aware that golf ball tees have heretofore been made of rubber and of paper, but rubber tees are necessarily expensive, and they are usually provided with strings to prevent their being lost, which string often detracts the attention of the golfer when addressing and striking the

ball. Paper tees litter the golf course, and their use is thus so objectionable that it is often prohibited. The present tee is so cheap that its loss is not a serious matter, and it is, therefore, unnecessary to attach a string to it, and, being soluble, the golf course is not littered up by its use.

We claim as our invention:

1. A golf ball tee comprising a tapered water soluble shell having a seat at its smaller end for a golf ball. 55
2. A golf tee composed of a water soluble material. 60
3. A golf tee composed of a substantially colorless transparent material. 65
4. A golf tee composed of a readily frangible sheet material. 70
5. A gelatin golf tee. 75
6. A golf tee composed of a substantially colorless, transparent water soluble material. 80
7. A golf tee composed of a substantially colorless, transparent readily frangible material. 85
8. A golf tee composed of a readily frangible, water soluble material. 90
9. A golf tee composed of a substantially colorless, transparent readily frangible, water soluble material. 95
10. A golf tee composed of formed sheet material and being substantially frusto-conical in form, the lower base being open and the upper base having a periphery adapted as a seat for a golf ball, said upper base being closed.

In testimony whereof, I have hereunto subscribed my name this 24th day of August, 1914.

ISAAC DE KAISER.
